PEDER C. THONER AND RUDOLPH M. MARTENS, BOTH OF BOSTON, MASSACHUSETTS.

COMBINED ICE AND SNOW SKATE.

1,159,897.

Specification of Letters Patent.

Patented Nov. 9, 1915.

Application filed May 8, 1914. Serial No. 837,157.

To all whom it may concern:

Be it known that I, OLE F. CHRISTIANSEN, of Bedford, in the county of Middlesex and State of Massachusetts, have invented certain new and useful Improvements in Combined Ice and Snow Skates, of which the following is a specification.

This invention relates to skates and has for its principal object the provision of a 10 skate which can be used with facility upon a hard surface such as ice or a relatively soft surface such as snow which is more or less packed.

A further object of the invention is to provide a skate having fastenings which will adapt it to be firmly secured to any kind of a shoe whether provided with a rubber heel lift or not.

With these and further objects in view the 20 invention consists in the improvements which I shall now proceed to describe and claim.

Of the accompanying drawings, Figure 1 is a side elevation of a skate embodying my 25 improvements, the snow runner being in raised position. Fig. 2 is a side elevation of the lower portion of the ice runner, with the snow runner adjusted to lower position for use. Fig. 3 is a plan view. Fig. 4 is a rear elevation with the parts in the relative positions shown in Fig. 1. Fig. 5 represents a section on line 5—5 of Fig. 1, omitting the runners.

Similar reference characters indicate similar parts in all of the views.

The foot plate as illustrated in the drawings comprises a toe section 10 and a heel section 11. The foot plate may, however, be otherwise formed and may be of metal or 40 wood. Rigidly secured to the foot plate is the ice runner 12 which may be of any suitable form. Said runner is provided with slots 13 the lower ends of which are offset rearwardly at 14.

45 The snow runner 15 comprises two sections each having a vertical flange 16 bearing against the side of the ice runner 12. The flanges 16 have apertures for screws 17 which pass through the slots 13, and are provided with nuts 18, said screws and nuts

serving as binding or clamping devices to hold the snow runner in any vertical position to which it may be adjusted. Since the screws 17 pass through apertures in the flanges 16, any vertical adjustment is caused 55 to be equal with both of the sections of the snow runner.

When the skate is to be used upon ice the snow runner occupies substantially the position shown in Figs. 1 and 4. When the skate 60 is to be used upon snow or other soft sliding surface which would be cut into too deeply by the ice runner, or if a person wishes to walk to the place for ice skating but is obliged to pass over a surface which would 65 either injure the ice runner or into which the ice runner would cut too deeply, then the screws 17 are loosened slightly and both screws are slid down the slots 13 and then pushed slightly rearwardly into the offset 70 portions of the slots, and the screws are then again tightened. This places the skate in the condition illustrated in Fig. 2 with the snow runner substantially flush with the lower edge of the ice runner. When a person 75 is wearing a pair of skates having the snow runners in substantially the position shown in Fig. 2, quite rapid progress may be made over packed snow or over snow that is not too soft by a movement somewhat 80 similar to roller skating. Or the skates may be used for coasting when in the condition illustrated in Fig. 2.

In order that the skate may be worn with practically any type of shoe, I provide fastening means which I shall now proceed to describe:—The front portion of the section 11 of the foot plate is slotted at 19 as indicated by dotted lines in Fig. 3. A screw 20 passes vertically through said slot and is 90 provided with set nuts 21. The head 22 of the screw is irregular as to its margins as indicated in Fig. 3 so that by turning the screw a different portion of the head 22 thereof may be employed to bite into the 95 front or breast of the heel of a shoe. Owing to the fact that the head 22 is offset or projects from one side farther than from another side, the positioning of the screw as described presents a binding edge which is 100

at a greater or lesser distance from the rear-most clamping member presently described according to the size of the heel that is to be gripped. Owing to the provision of the 5 screw 20 and nuts 21, the head 22 may be set at such a height as may be necessary to best engage the breast of a heel. In Fig. 1 the heel of the shoe is represented as having a rubber tread. The vertical adjustment of 10 the gripping or biting member 22 enables it to be located high enough to insure a tight connection with the heel without exerting any strain upon the rubber tread. The slot 19 provides for an adjustment of the screw 15 20 forward or back.

At the rear of the heel plate 11 is a rigid slotted upright 23 through which a screw 24 passes horizontally, said screw having a plate 25 swiveled to its front end said plate 20 having a biting flange 26 and also a friction pad 27. The screw 24 engages and passes through an internally threaded bolt 28 the outer sides of which are flattened to engage the walls of the slot of the upright 25 23 so that said bolt cannot rotate in said slot. The head 29 of the bolt engages one side of the upright 23 and a set nut 30 fitted to an external portion of the bolt 28 engages the other side of the upright 23. By means 30 of the nut 30 the bolt 28 may be secured in proper vertically adjusted position to meet the requirements of any shape and height of heel, and the screw 24 may be rotated by means of a wrench engaging its outer end 35 so as to force the biting flange 26 or the friction pad 27 against the rear of the heel of a shoe, thereby co-acting with the front gripping member 22 in securing the skate to the shoe heel. Owing to the swiveled 40 connection of the plate 25 with the inner end of the screw 24, said plate 25 may be rotated so that either its biting flange 26, or the friction pad 27, may bear against the rear of the shoe heel.

45 The toe straps 31 are pivotally connected at 32 to the section 10 of the foot plate. Each strap is provided with an adjustable sole edge gripper 33 which consists of a metallic plate having lips 34 which embrace the strap section. As indicated in Fig. 5 the members 33 are of an angular shape to fit the edges of a shoe sole. Owing to their angular formation and the lips 34 which extend around the edges of the strap, the 50 members 33 cannot slip. The two strap sections may be connected by a suitable buckle 35. Preferably the pivoted ends of the strap sections fit in depressions 36 in the plate 10.

60 Many skaters do not like to rely solely upon sole edge grippers because unless the shoe fits very tightly there is not the same feeling of security as when a toe strap is

employed. The ordinary toe strap, however, permits the foot to shift laterally across the 65 toe portion of the foot plate. By my improved attachments 33, the foot is prevented from slipping sidewise. Owing to the pivotal connection of the strap section with the foot plate the straps can be swung so that 70 the grippers 33 will engage the side edges of the sole of a shoe firmly, without marring the same, no matter whether the sole is more or less tapering.

In order to further guard against slipping 75 of the grippers 33 I may form prongs 37 therein, said prongs being pointed as indicated by comparing Figs. 3 and 5, to bite into the leather of the straps. When the member 33 is to be adjusted along the strap, 80 the strap is pulled through the lips sufficiently to release the strap from the prong, and then after shifting the gripper along the strap the strap is again pulled tightly so that the prong 37 will bite thereinto.

85 In Fig. 1 I have indicated by dotted lines the lower portion of a shoe to which the skate is attached. As illustrated in said figure the biting flange 26 enters the recess or groove at the top of the heel of the shoe 90 while the friction pad 27 bears firmly against the rear of the heel. As will be readily understood the adjustability of the rear heel clamping member enables it to be so mounted as to engage the portion of the heel indicated in Fig. 1, thereby avoiding any marring whatever of the rear of the heel.

95 What I claim is:

1. A skate having a foot plate provided with gripping members for the front and back of a shoe heel, said gripping members being vertically adjustable independently of each other.

100 2. A skate having a foot plate provided with vertically and horizontally adjustable heel gripping members.

105 3. A skate having a gripping member for the breast of a shoe heel, said member being rotatable and having heel engaging portions at different distances from the axis of rotation.

110 4. A skate having a gripping member for the rear of a shoe heel, said member being rotatable and provided with a biting edge and a friction pad.

115 5. A skate having the rear portion of its foot plate provided with a slotted upright, and a heel gripping member longitudinally and vertically adjustable in the slot of the upright.

120 6. A skate having a foot plate, a toe closure consisting of flexible straps connected to the foot plate, and a pair of sole-engaging members independently adjustable along said straps.

125 7. A skate having a foot plate, straps piv-

totally connected to the foot plate, and sole-engaging members adjustably carried by said straps.

8. A skate having a foot plate, straps pivotally connected to the foot plate, and sole-engaging members adjustably carried by said straps, said members comprising angular plates on the inside of the straps and

having lips embracing the edges of the straps.

In testimony whereof I have affixed my signature, in presence of two witnesses.

OLE F. CHRISTIANSEN.
